Attorney:

UNITED STATES PATENT OFFICE.

JOE HAVASSY, OF COPPERHILL, TENNESSEE.

FILTER AND WATER-COOLER.

No. 902,076.

Specification of Letters Patent.

Patented Oct. 27, 1908.

Application filed April 20, 1908. Serial No. 428,122.

To all whom it may concern:

Be it known that I, JOE HAVASSY, a subject of the King of Hungary, residing at Copperhill, in the county of Polk and State 5 of Tennessee, have invented certain new and useful Improvements in Filters and Water-Coolers; and I do declare the following to be a full, clear, and exact description of the invention, such as will enable others skilled 10 in the art to which it appertains to make and use the same.

This invention relates to improved means for housing and connecting a water cooler and filter with a water supply pipe and the 15 object of the invention is to provide simple and efficient means of this character.

For these and still other objects which will appear as the description proceeds the invention consists of certain novel features, arrangements and combinations of parts of 20 which the herein described filter and water cooler is one of many possible embodiments.

While herein the description refers to minute details of the invention, the invention 25 is not limited to these as the details of construction and combination may be greatly varied without departing from the spirit and scope of the invention.

In the annexed drawing forming a part of 30 this specification in which like reference characters refer to like parts throughout the several views and which are for illustrative purposes only and therefore not drawn to any particular scale.—Figure 1 represents a 35 vertical section of this combined filter and cooler showing it housed within a recess formed in the wall of a room and connected with a water supply pipe; Fig. 2 is a horizontal sectional view taken on line 2--2 of 40 Fig. 1.

In the embodiment illustrated, this improved apparatus 1 is shown housed within a recess within a kitchen wall the recess being 45 shown of sufficient size to permit the hand and arm of a person to be inserted around the apparatus for turning on or cutting off the water supply by means of a cock 2, the apparatus being connected with the main supply pipe 3 by means of a suitable coupling 4 which is so constructed as to permit 50 the apparatus to be detached when desired for cleaning or other purposes.

This apparatus is preferably made in the 55 form of a double box, the inner box member 6 being composed of iron with an outer covering 6 thereof spaced from the iron box

member and composed of wood or any other suitable material. The space between the outer wooden box and the inner iron box is preferably filled with saw-dust as 7 or any other suitable material. A filter 8 is arranged within this double box and spaced therefrom a suitable distance to provide an ice chamber 9. This filter is preferably provided with a space 11 here shown as arranged at the top in which broken rock or stone is suitably supported on a perforated plate 12, detachably mounted within the filter 8 preferably on supporting flanges as 13. The space 14 below the rock containing space 70 is filled with charcoal, supported on a suitable perforated plate 15 and ground gravel as 16 is arranged in the space below that filled with the charcoal and is supported on a suitable screen or perforated plate 17. A 75 plurality of strainers 18 of different mesh, are suitably supported below the gravel containing compartment and are designed to more thoroughly filter the water as it passes therethrough to the compartment 19 arranged below the filter.

The ice containing compartment arranged between the filter and the walls of the double box is separated from the compartment 19 which receives the filtered water and is provided with a spigot 20 for drawing off water resulting from the melted ice. A faucet 21 is also provided for the compartment which contains the filtered water. The filter is also preferably provided with a top 22 preferably provided with a suitable packing 23 for rendering it water-tight, and the outer double walled box is provided with a cover 24 to afford access to the ice chamber and to the filter.

A pipe 25 is arranged below the apparatus 1 and connected with the main water supply pipe 3 through which unfiltered water may be supplied to the kitchen when it is not desired to use the cooled and filtered 100 water. A pipe 26 opens into the upper end of the filter and is connected with the coupling 4 to provide for the passage of the unfiltered water through the various layers of filtering material.

I claim as my invention:

The combination with a wall having a recess therein and a water supply pipe arranged at the back of said recess, of a combined cooler and filter housed within said recess and spaced from the walls thereof, a valved pipe connecting said filter with said

water supply pipe and a coupling arranged in said pipe to provide for the disconnection of the filter when desired, faucets for drawing off the iced and filtered water, respectively, and a pipe extending through said wall and connected with said supply pipe.

In testimony whereof I have hereunto set

my hand in presence of two subscribing witnesses.

JOE HAVASSY.
